[57] CLAIM

The ornamental design for a weathervane support, as shown and described.

DESCRIPTION

FIG. 1 is a perspective view of the weathervane support of the present invention;

FIG. 2 is a side view of the weathervane support of FIG. 1;

FIG. 3 is a top plan view of the weathervane support of FIG. 1;

FIG. 4 is a bottom view of the weathervane support of FIG. 1;

FIG. 5 is a front end view of the weathervane support of FIG. 1; and,

FIG. 6 is a back end view of the weathervane support of FIG. 1.

The broken line showing is for illustrative purposes only and forms no part of the claimed design.
